UNITED STATES PATENT OFFICE

ANTON FAZEKAS, OF SAN FRANCISCO, CALIFORNIA

ELECTRIC HEATING ELEMENT

Application filed September 16, 1929. Serial No. 392,903.

My invention relates to improvements in electrical heating elements wherein a plurality of arcuate heating elements are held in longitudinally parallel spaced relation to 5 form a heating chamber for fluid within a container or compartment.

The primary object of the present invention is to provide a new and improved article of manufacture comprising an improved electrical heating element. 10

Another object of the present invention is to provide a new and improved article of manufacture of the character set forth having new and improved means for providing 15 a heating chamber for heating fluid within a container.

A further object is to provide an improved device of the type described which may be easily and economically manufactured and 20 which shall have a maximum efficiency.

A still further object is to provide a heater as described having a pocket within a heating chamber wherein circulation is more or less retarded whereby a small quantity of 25 fluid is quickly heated to a comparatively high degree and ejected from said pocket by the expansion due to said increase in temperature, thereby inducing a circulation which will force adjacent fluid of a lesser 30 degree of temperature into said pocket where it may in turn be heated.

I accomplish these and other objects by means of the improved device disclosed in the drawings forming a part of the present application wherein like characters of reference are used to designate similar parts throughout the specification and drawings, and in which— 35

Fig. 1 is a side elevation of my improved electrical heater and showing a portion of a fluid heater to which it may be attached; 40

Fig. 2 is a vertical longitudinal sectional view taken on line 2—2 of Fig. 1 in the direction indicated; 45

Fig. 3 is a broken sectional view of one of the heating elements removed from the device;

Fig. 4 is a transverse sectional view taken 50 on line 4—4 of Fig. 1;

Fig. 5 is a transverse sectional view taken on line 5—5 of Fig. 2; and

Fig. 6 is a bottom view in elevation of Fig. 2.

Referring to the drawings the numeral 1 is used to designate in general any suitable fluid container having an internally threaded aperture 2 for the reception of what I term a head 3 provided with a threaded portion 4 and an annular collar 6 extending inwardly 55 from said threaded portion 4.

The head 3 is provided with a transverse wall or partition 7 having a plurality of arcuate slots 8 therein within which slots 8 are mounted water-tight heating elements 9, said 60 heating elements 9 being thus arranged in longitudinally parallel spaced relation to each other to form and surround a central heating chamber.

Within each element 9 are inner and outer 70 insulation sheets 11 and 12 respectively and between the two are resistance coils 14 of suitable design.

The ends of the resistance coils 14 are connected to suitable terminals 16 mounted 75 within a porcelain or other insulated disc 17 mounted within the head 3 and on the outer side of the wall or partition 7, as disclosed in Fig. 2 of the drawings.

In order to provide further efficiency in 80 several directions, if it is desired a tube 18 may be inserted within the spaced elements 9 to more rigidly retain said elements 9 in proper spaced relation, said tube 18 being apertured as at 19 opposite the spaces between the elements 9 and beyond the inner end of the annular collar 6 to permit the passage and circulation of fluid between said elements 9 and thereby into the heating chamber surrounded by said elements 9. 90

It will be observed, by referring to Fig. 2 of the drawings that a pocket A has been formed within the annular collar 6 and threaded portion 4 of the head, and, by the insertion of the tube 18, smaller pockets B 95 are provided between adjacent edges of the elements 9 and the said tube 18 and annular collar 6. There being practically nothing to induce circulation in these several pockets A and B it is obvious that the fluid therein, 100

when the heater is in operation, will be rapidly heated to a high degree of temperature and the pressure due to expansion in turn due to the rise in temperature will eject the heated fluid from said pockets and thereby tend to facilitate the entrance into said pockets of surrounding fluid of lesser temperature which will in turn be heated, thereby rapidly radiating heat into the fluid body and heating the same.

Also, while the heating elements are in operation, the fluid within the heating chamber surrounded by the heating elements 9, as well as fluid surrounding said elements, will be heated by close proximity to said heating elements 9 but it is obvious that the fluid within the heating chamber will receive a greater degree of heat from said element within the same period of time, and as said fluid within the chamber is heated to a certain degree it will rise and induce a circulation of fluid from around the outside of said elements and through the longitudinal spaces between said elements into said heating chamber.

This process will continue as long as the heater is in operation until the fluid within the heater has been heated to the capacity of the heater.

It is obvious that the circulation thus produced will ultimately bring practically all of the fluid within the container through the heating chamber whereby it will be effectively heated.

Having thus described my invention what I claim as new and desire to secure by Letters Patent is—

1. An electric heating unit comprising a head provided with a plurality of heating elements each consisting of a resistance coil enclosed in a fluid tight casing, said casings being arcuate in cross section and arranged in spaced relation about the axis of the head to form a heating chamber to contain a fluid to be heated whereby said fluid may circulate through the spaces between the coil casings and be retained in proximity to said heating elements for a period.

2. An electric heating unit comprising a head provided with a plurality of heating elements each consisting of a resistance coil enclosed in a fluid tight casing, said casings being arranged in spaced parallel relation to each other about the axis of the head to form a heating chamber adjacent said elements and for containing a fluid to be heated, said fluid flowing into the chamber through the spaces between the coil casings and being retained therein until the expansion of said fluid, due to said heat, causes said fluid to be ejected from said chamber by said expansion and thereby facilitates circulation of surrounding fluid into said chamber.

3. An electric heating unit comprising a head for insertion into a fluid container; and

a plurality of heating elements mounted upon said head and arranged in spaced relation to form a heating chamber between said elements for containing a fluid to be heated by said elements, each element comprising a resistance coil enclosed within a fluid tight casing, the edges of the casing being spaced to permit circulation of fluid into the head and the chamber between the elements; and means for detachably securing the unit within a fluid container.

4. An electric heating unit comprising a head for submerged insertion into a fluid container; a tube extending axially from the head and having apertures in the walls thereof; and a plurality of arcuate heating elements mounted upon said head in spaced parallel relation in proximate relation to the surface of the tube to form a heating chamber, the space between said elements matching with the apertures of the tubes to permit a circulation of fluid into the chamber for heating fluid within said chamber as well as for heating fluid surrounding said elements.

5. An electric heating unit comprising a head provided with a threaded annular collar for securing the head submerged within a fluid container; and a plurality of arcuate heating elements mounted within said annular collar and arranged in spaced parallel relation with each other to form a heating chamber whereby a fluid within said chamber as well as fluid surrounding said elements may be heated by said elements.

6. An electric heating unit comprising a head provided with a threaded annular collar for securing the head submerged within a fluid container, said head being provided with a transverse wall provided with arcuate slots; a plurality of arcuate heating elements mounted within said collar and extending into said container and likewise extending through the arcuate slots of the transverse wall and arranged in parallel spaced relation to form a heating chamber surrounded by said heating elements; and a tube inserted within said heating chamber to retain said heating elements in proper spaced relation, said tube being apertured opposite the spaces between said elements to permit entrance of fluid into said heating chamber.

7. An electric heating unit comprising a head provided with an annular threaded collar for securing said head within a fluid container, said head being provided with a transverse wall having arcuate slots therein; a plurality of arcuate heating elements mounted within said slots and extending beyond said annular collar and thereby held in parallel spaced relation with each other to form a heating chamber surrounded by said elements; and a tube mounted within said heating elements and collar and apertured beyond said collar opposite the spaces between the elements to permit the circulation of

fluid through said heating chamber and also providing additional heating chambers in the spaces between adjacent edges of said elements, and the tube and annular collar.

5 8. An electric heating unit comprising a head provided with a recessed body detachably mountable within a fluid container; a plurality of heating elements each consisting of a resistance coil enclosed in a fluid tight 10 casing mounted in spaced parallel relation upon the body and extending longitudinally outwardly from the recess of the body to form a heating chamber between the elements, said chamber having a pocket formed within the 15 recess of the body, fluid being admitted into said pocket through the spaces between the elements whereby said fluid may be partially confined and heated to induce circulation of fluid through the chamber.

20 In witness whereof, I hereunto set my signature.

ANTON FAZEKAS.
